FIG. 6

UNITED STATES PATENT OFFICE.

JAMES McGARVEY, OF MALDEN, WASHINGTON.

GRAIN-TRANSFERRING DEVICE.

Application filed January 12, 1925. Serial No. 1,983.

This invention relates to an improved means for transferring comminuted material such as grain.

The device of my invention, while not thus limited, was especially designed for transferring grain from a bad order freight car to a car in good order. In this connection, the invention was designed to be pneumatically operated from the air pipes in the yard.

It is one of the objects of this invention to provide a grain transfer device that is adapted, initially, to be buried in the body of grain to be transferred, as regards the intake end of the device; the arrangement being such that the action of the device in transferring the grain will cause the device to gradually sink in the grain body as the level of the latter descends, whereby the device will always be below the grain level until the device reaches the floor of the grain car. In some cases, the intake end of the device can be initially buried in the grain body at the extreme bottom thereof.

A further feature of my invention consists in a novel manner of employing air under pressure so that the air will act as an injector to draw the grain into its path and cause propulsion of the grain through a tubular conveyor to the desired point of transfer.

A further feature consists in providing an intake end which is in the form of a housing and which is provided with a relatively enlarged intake portion of a shovel-like formation to facilitate insertion of the device into a buried relation with respect to the wheat or other grain body.

My invention has many other features and objects that will be more fully described in connection with the accompanying drawings and which will be more particularly pointed out in and by the appended claims.

In the drawings:—

Fig. 1, is a cross sectional view of a bad order freight car from which grain is being transferred.

Fig. 2, is a cross-sectional view of a good order car into which the grain is being delivered.

Fig. 3, is a horizontal sectional view of the car shown in Fig. 1.

Fig. 4, is a similar view of the car shown in Fig. 2.

Fig. 5, is a plan view on an enlarged scale showing the intake portion of the transferring device.

Fig. 6, is a horizontal sectional view thereof.

Fig. 7, is an end view looking from the left of Fig. 6.

Fig. 8, is a longitudinal sectional view on line 8—8 of Fig. 6.

Like characters of reference designate similar parts throughout the different figures of the drawings.

I will first describe the structure of my device and will subsequently detail the manner in which the same operates.

The device is indicated as a whole at 1, and the same has an intake portion 2 and a discharge portion 3. An important part of the device consists of a conveyor 4, which is preferably in the form of a hose, which is flexible, and which in practice, has substantially a three inch internal bore. The discharge end 3, may be equipped with a nozzle if desired, but in practice, a nozzle is not essential as I obtain the best results by using a discharge end of the full diameter of hose employed. It is desirable that the discharge end 3, should not be covered with grain as that would unnecessarily load the device with a back pressure and retard speed.

The intake end 2, of the device preferably includes a metal union 5, into which the end 6, of the hose 4, is suitably secured, the same being shown as internally telescoping union 5, in air tight relation thereto.

Reference will next be made to the housing, which constitutes the most important part of the intake end of the device.

As shown, this housing has a bottom wall 7, a top wall 8, and side walls 9. As will be seen in the drawings, the housing tapers from its intake end toward union 5, into which the tubular end 10, of the housing, is suitably secured in air tight relation. Such air tight relation of the parts is not the character of air tight fit that is necessary in air brakes or any character of mechanism where air pressure is essential up to a required minimum. This is because my improved device works on the injector principle and hence slight leakage would not materially effect the efficiency although it is desired to reduce leakage to a minimum. It will be noted that bottom wall 7, is trans-

versely bowed, as shown in Fig. 7, thereby increasing the intake capacity and, by reason of the metal construction, facilitating insertion of the housing into the grain. The top 5 wall 8, terminates at 11, and the side walls 9, at their rear edges, are inclined downwardly as at 12, so that the intake opening for the housing is of a shovel or scoop-like nature. Further, by reason of the shortened upper and side walls, the housing intake opens not only upwardly, but also endwise and laterally of the longitudinal axis of said housing whereby the greatest possible ingress capacity is afforded to the grain, 10 15 comparable to the size of the housing.

The housing is equipped with an air pipe for supply of air under pressure to pneumatically operate the device.

As shown, 13 designates an air pipe which 20 is preferably secured to the housing by straps 14 and 15, as clearly shown in Fig. 5. A manually operable valve 16, having a hand lever 17, is interposed in the pipe so that the operator can control the air at all times. 25 The pipe 13, terminates in an air coupling 18, adapted to be coupled to a companion fitting on the air hose 19, from the rip track, or from any other suitable source of sustained supply. I have shown an elbow 20, 30 connected with an elbow 21, the latter having the injector section 22, of the air pipe. This injector section 22, extends between the top and bottom walls 8 and 7, respectively, and toward the coupling 5, and is held in 35 this position by the rigid connection of the air pipe 13, with the housing. It will be noted that the terminal end 23, of said section 22, extends appreciably to the right of edge 11, of the top wall 8, and very near to the most restricted portion of the housing. 40 As the air discharges from end 23, it induces a flow of the grain into and through the housing. As the grain proceeds to a point in advance of the end or nozzle 23, the air 45 propels the grain.

In order to get the proper constriction to obtain efficient injector action, and to avoid a malformation of the housing which would weaken the latter, I provide means which is 50 disposed within the housing to obtain the desired injector restriction.

As shown, I have disposed stiffening partitions 24, alongside section 22 from a point substantially in the rear of said nozzle 23, 55 to a point sufficiently in advance thereof to meet the taper or restriction of the side walls 9. These partitions are preferably flanged, as indicated at 25, and riveted or otherwise secured to the top and bottom walls, as 60 shown at 26. It will be seen that there is a slight convergence of the partitions 24, from left to right of Fig. 6, and it will also be seen from Fig. 8, the outer edges 27, recede from the top to the bottom wall. By thus 65 receding the ends 27, I reduce the resistance

of ingress along the top of bottom wall 7, and yet, I provide the required extension of constriction to a point almost to the edge 11, of top wall 8. As a result of this disposition of the partitions, the grain has practically an unobstructed entrance onto the top of bottom wall 7, to a point substantially in the rear of the edge 11, of top wall 8. This disposition of partitions 24, forms chambers 70 75 28, which are dead chambers, without any function, but which are of such limited capacity that they are not objectionable.

With the structure thus far described, unless it were shoved into the grain body sufficiently to fill the housing to a point substantially abreast of nozzle 23, the action of transferring would start slowly. It would also be difficult to sustain operation. Therefore, to facilitate priming, and to adequately sustain operation, I provide in the 80 top wall 8, a priming and auxiliary feed opening 28, which, as will be noted, opens upwardly toward the grain above the buried housing. It will be noted that dotted line A, shows that the nozzle 23, is slightly in the 85 rear of the farthest diametrical portion of the opening 28, to the right of Fig. 8. This disposition, allows most of the grain to be 90 fed into the housing, through opening 28, in the rear of nozzle 23. 95

I will next describe the operation of my device, with particular reference to the transfer of grain from one freight car to another.

It will be assumed that B designates the 100 bad order car and C designates the car in good order. The door openings of the respective cars are designated at b and c, the sliding doors at b' and c'. Inside the side walls of the cars, boards b² and c² retain the 105 grain or other contents of this character from leaking out. In some instances, I can saw an opening in the bottom board, as indicated at b³ and insert the housing with only a slight leakage of grain, the latter 110 being shovelled back into the car. The hose 4, is extended over the retaining boards c² of the adjacent car C, as shown. A rip track air hose 19, which is always available, is connected up with its fittings with hose 115 4, as shown at 18. Now the valve 16, is opened, and the air under pressure induces and forces the grain from housing 2, through the hose 4, into car C. It is desirable, although not essential, that the end 3, should 120 not be buried in the grain of car C, because of back pressure load imposed upon the injector. However, in practice, I find that if the free end 3, is manually unrestrained, it will wobble and wiggle under the action of 125 the air pressure to such an extent that it can hardly become buried. Thus, in practice, I have allowed the end 3 to be free, until the middle of the car has been filled. After the 130 middle of the car has been filled, it is the

practice for a man to direct the hose 4, toward one end of the car, and then toward the other end, so that the car C, can be completely filled without any shovelling at all. This hose 4, will be of sufficient length so that after the grain from the center of car B, has been withdrawn, the housing 2, can be advanced toward the ends of car B.

I next wish to point out novel features of the invention whereby the action of the device itself, will act to bury the housing in the grain.

In full lines in Fig. 1, I have shown the housing 2, initially buried beneath the grain level as shown by dotted line E. As long as the housing is buried to the extent of getting opening 28, beneath the grain level, this is sufficient. It will also be noted that the metal edges 30, 12 and 11, will offer very little resistance to insertion of the housing as shown. In this inclined position shown in full lines, the displacement of the grain into the housing, will act as a suction tending to draw the housing to a further depth into the grain as the latter enters the housing. For instance, just as soon as the grain in the immediate proximity of the housing entrance, has entered the housing, a void is created which allows the housing to further descend. This, together with a sort of suction action, will cause the housing to sink gradually lower in the grain body to be transferred, as the level of said body descends, and this is entirely automatic.

It will be seen that the partitions 24, are so disposed and related with respect to the nozzle 23 as to efficiently initiate and sustain injecting action. Further, by reason of these partitions, I obtain the requisite restriction to obtain injecting action and also do not require an abrupt convergence of the side walls 9, which would otherwise be necessary if it were not for the partitions 24.

It will be seen that aside from valve 16, the whole structure is devoid of movable parts, all the parts being rigid, and in rigid connection with each other. Such adjustment of the nozzle 23, lengthwise, to the required position with respect to the restrict-

ing partitions 24, and with respect to opening 28, may easily be made by turning the section 22 in the fitting into which it is screw threaded.

From the foregoing description, it will be clear that I have devised a mechanism which is readily hand portable, and in practical use, I have very greatly reduced the cost of transferring grain from bad order cars.

It is believed that the method and apparatus of my invention will be fully understood from the foregoing description, and while I have herein shown and described one specific form of my invention, I do not wish to be limited thereto except for such limitations as the claims may import.

I claim:

1. A grain transferring mechanism including a housing tapered from its intake end toward its discharge end, an air injector pipe in said housing extending toward the discharge end thereof, and partitions in said housing alongside said pipe restricting the area of the interior of said housing to coact with said pipe to initiate injection action to advance the grain.

2. A grain transferring mechanism including a housing tapered from its intake end toward its discharge end, an air injector pipe in said housing extending toward the discharge end thereof, and means in said housing and alongside said pipe for restricting the area of said housing adjacent the discharge end of said pipe to initiate injection action and advance the grain.

3. A grain transferring mechanism including a housing tapered from its intake end toward its discharge end, an air injector pipe in said housing extending toward the discharge end thereof, means in said housing and alongside said pipe for restricting the area of said housing adjacent the discharge end of said pipe to initiate injection action, and said housing having an opening for ingress of grain into said restricted area to prime and sustain injection action.

In testimony that I claim the foregoing as my own, I hereby affix my signature.

JAMES McGARVEY.
